UNITED STATES PATENT OFFICE.

FAY T. RODGERS, OF MEMPHIS, TENNESSEE.

REFRIGERATOR.

Application filed October 16, 1926. Serial No. 141,931.

This invention relates to improvements in refrigerant containers for refrigerators and especially to containers which are used for holding a mixture of salt and ice.

- Among the objects of this invention, are to provide an ice container which,—
 (a) Will be simple in construction;
 (b) May be easily filled;
 (c) Will separate the refrigerant and provide for the easy passage of air therethrough, and
 (d) Will provide a maximum amount of cooling surface with a minimum of expense.

The means by which these and other objects are accomplished, and the manner of their accomplishment, readily will be seen in the following description on reference to the accompanying drawings, in which

Fig. 1 is a sectional prospective view of one end of a refrigerator with a refrigerant container therein, the end of the ice container having been cut away to show the interior construction thereof.

Fig. 2 is a longitudinal section of the container being the line II—II of Fig. 3, and

Fig. 3 is a sectional elevation on the line III—III of Fig. 2.

Referring now to the drawings in which the various parts are referred to by numerals, 10 is the casing of the refrigerator made in any usual manner. 11 is a door in the top thereof through which door the refrigerant container may be raised or lowered and through which door it may be filled with a refrigerant such as ice and salt. This container comprises a bottom 12, perforated sides 13 and one perforated end 14. The opposite end 15 of this container being the one away from the end of the refrigerator in which the container is located and being the end shown in Fig. 3, is preferably without perforations.

Disposed within the container are inclined shelves 16, which preferably extend from end to end thereof and are suitably attached to the side and end walls, as by rivets 17, 18, the shelves being provided with flanges 19 and 20, to permit of such attachment. The container is preferably supported above the bottom of the refrigerator as by supports 21, which rest on the bottom.

It will be understood that while only one

container is shown, the refrigerator box may be made with spaces at both ends for the 55 refrigerant containers and one container be used at each end of such a box, or if it be desired, the container or containers may be otherwise located therewithin.

In use the door 11 is removed and the 60 container lowered into the refrigerator and is then filled with crushed ice and salt. When so filled part of the ice and salt will be retained on each of the shelves and part in the central part thereof resting on the 65 bottom. Even when freshly filled spaces will be left through which air may circulate, and as the ice melts such condition is accentuated. The warm air within the 70 refrigerator rises to the top and as it comes in contact with the refrigerant container, is cooled, causing it to drop. The open spaces between the masses of refrigerant allows the air to pass through the container as well as around the outside of the same 75 and establishes a large cooling surface. The disposition of the shelves allows this air to pass downward and partially to be diverted outward through the perforations in the sides of the containers. It also allows 80 additional air to pass directly downward through the center of the container and the circulation of air thus set up, eventually causes a very thorough and efficient circulation of the air within the refrigerator 85 itself, and an extremely efficient cooling action.

Much effort has previously been expended in an endeavor through the use of tubes and other devices, to open up a passage-way 90 through the refrigerant whereby a large cooling surface may be exposed to the action of the air, a result which has been efficiently and simply obtained in the present construction by the separation of the refrigerant 95 within the container so that free circulation therethrough may be had.

It will of course be understood that the drawings herein are for purposes of illustration only, and that I do not wish to confine myself to the exact details herein shown, except in so far as such details may be specifically set out in the claims.

Having thus disclosed the invention, what 100 is claimed is:—

A refrigerant container, comprising a

bottom, sides having perforations there-through, and ends, and a plurality of oppositely disposed shelves each permanently secured to a side and the said ends and extending upward from said side at an angle thereto, said shelves being considerably less than half the width of said container,

whereby a central open space is left between said shelves to permit filling said container without removal of said shelves. 10

In testimony of the foregoing I affix my signature.

FAY T. RODGERS.
